SOLE AND HEEL COMBINATION FOR SHOES

Borys Bekierman, New York, N. Y.

Application July 2, 1952, Serial No. 20,452

Term of patent 7 years

(Cl. D7—5)

To all whom it may concern:

Be it known that I, Borys Bekierman, a citizen of no country, residing in the city of New York, in the county of New York, and State of New York, have invented a new, original, and ornamental Design for a Sole and Heel Combination for Shoes, of which the following is a specification, reference being had to the accompanying drawing, forming part thereof, in which:

Fig. 1 is a side elevational view of a sole and heel combination for shoes embodying my new design,

Fig. 2 is a top plan view thereof; and Figs. 3 and 4 are front and rear elevational views, respectively, of the sole and heel combination.

I claim:

The ornamental design for a sole and heel combination for shoes, as shown.

BORYS BEKIERMAN.
